UNITED STATES PATENT OFFICE

JESSE G. KING, OF DAYTON, OHIO, ASSIGNOR, BY MESNE ASSIGNMENTS, TO GENERAL MOTORS RESEARCH CORPORATION, OF DAYTON, OHIO, A CORPORATION OF DELAWARE

PUMP FOR REFRIGERATION SYSTEMS

Application filed July 19, 1920. Serial No. 397,519.

The present invention relates to apparatus for refrigeration and more particularly to improvements in compressors especially adapted for such apparatus.

5 Among the objects of the invention is the reduction of friction between moving parts of the compressor driving means, and at the same time preventing leakage of oil and refrigerant from the system and of air into the 10 system.

Another object of the invention is to provide an improved power transmitting device in which the driving and driven elements are completely sealed from each other by a fluid 15 tight partition. More specifically it is an object of the invention to provide an improved power transmitting device in which the elements are sealed from each other by a flexible metal partition.

20 Another object of the invention is to so arrange such a partition that it will have great endurance or long life.

Another object is to so arrange the partition that it will be subjected to the minimum 25 stress under operating conditions.

Further objects and advantages of the present invention will be apparent from the following description, reference being had to the accompanying drawings, wherein a preferred 30 embodiment of the invention is clearly shown.

In the drawings:

Fig. 1 is a vertical longitudinal section of the compressor showing certain portions in 35 elevation.

Fig. 2 is a similar view with the section taken at right angles to that of Fig. 1.

Fig. 3 is a diagrammatic representation of 40 a refrigeration system showing the compressor or pump somewhat enlarged with respect to the remainder of the system, and showing its relation thereto.

Figs. 4, 5, 6, 7 and 8 illustrate certain 45 details of the apparatus.

The known refrigeration systems comprise a compressor to compress the refrigerant gas; a condenser for cooling and condensing to a liquid the compressed gas, and an expansion chamber wherein the liquefied refrigerant is allowed to expand and in the expansion absorb heat from the atmosphere or other me-

dium surrounding the chamber. The usual expansion chamber is in the form of a coil submerged in a tank of brine, the expansion of the gas abstracting heat from the brine and chilling it to the desired low temperature. 55

In the known systems, difficulty has been experienced in preventing leakage of the refrigerant from the apparatus and attempts have been made to reduce or overcome this leakage. If the compressor is not enclosed but is provided merely with an inlet and an outlet for gas, leakage may occur around the piston or at other places. If the compressor is enclosed in a chamber and driven by means of a shaft through the wall of the chamber, there is necessitated a packing gland for the shaft. This construction is found in a number of refrigerating systems but it does not eliminate entirely leakage of gas or oil and produces considerable friction, thus causing 60 a waste of power. 70

In the construction shown in the drawings, the compressor is enclosed in a chamber and driven by a motor or other source of power positioned outside of the chamber, but the packing gland has been eliminated and there has been substituted in its place an effective seal for the chamber, thus preventing leakage of either refrigerant or oil from the system or air into the system. 75 80

In the construction shown in the drawings, which construction is a preferred embodiment of the invention, the pump comprises a housing 10 which is adapted to enclose the pump cylinders and pistons. In the form shown, the housing is provided with a base portion 10^a and two opposite and aligned cylinders 11 in its upper portion. Extending laterally from the cylinders and suitably secured to the base portion 10^a is a crank case 85 90 portion 10^b adapted to receive the driving mechanism hereinafter to be described.

Operating within the cylinders 11 are pistons 12, and these pistons are shown as carried upon the two ends of a single piston rod 13. 95

The pistons 12 may be of any suitable or desired form, but the form indicated in the drawings, has been found to be satisfactory and to give excellent results and is the form 100

preferred. This form of piston comprises a main piston member 20 having a longitudinal bore, forming at its upper end a valve seat 21. The piston member 20 is provided with the usual annular grooves for piston rings and at its lower or skirt end with suitable slots or openings for the members 22 which retain the piston upon the piston rod 13. The piston rod in turn is provided with slots coacting with the members 22 and of such width as to allow the movement of the piston rod longitudinally within the piston member 20. This piston rod is provided with a longitudinal opening 23 extending from near its central portion to within a short distance of its end. At a suitable point near the ends of the piston rod lateral openings extend from the passage 23 into an annular space 24 within the piston member 20. The piston rod is also provided at its end with the valve surface 25 coacting with the valve seat 21 within the end of piston member 20. The annular space 24 above referred to, is in direct communication with this valve formed in the end of the piston.

This form of piston provides a positively actuated inlet valve as well as a suitable form of compressor piston.

The piston rod 13 may be reciprocated by any suitable driven member having a power transmitting connection with a driving member outside of the housing 10. I prefer to operate the piston rod by means of a driven member partaking simultaneously of motion in different directions, one of which may take place principally inside of the housing 10 and the other of which may take place principally outside of the housing 10. These different motions may for example, be simple planar oscillation simultaneously in opposite directions as illustrated in Fig. 1.

In the present modification piston rod 13 carrying the pistons 12 is actuated by means of a driven member in the form of a pivoted lever designated as a whole by the numeral 40. This lever is pivoted at a point intermediate its ends, the end opposite the pump being adapted to be oscillated by means of a crank connected to a suitable driving means.

The central portion of the piston rod is provided with a slot 26, and passing through the rod and the slot is a pin 27 upon which is journaled a block 28 having flat bearing surfaces for a fork 29 formed on the actuating lever or walking beam 40.

In the form illustrated, the lever 40 is provided with outwardly and downwardly extending arms 41 provided at their lower ends with bearings journaled upon suitable spindles or pivots 42 supported in the walls of the housing. At a point immediately below the junction of the arms 41 with the main or body portion of lever 40, this body portion of lever 40 is provided with a disc portion 45 having upon its under side an an-

nular groove 46, the purpose of which disc and groove will be explained later. The lower main portion of the lever is screw-threaded and carries a fork member 43 fastened thereto by means of a nut 44. This fork member 43 has its upper portion in the form of a sleeve fitting over the lower portion of the lever 40. This fork 43 coacts with a driving member in the form of a crank 50, a suitable ball-bearing 51 being provided to reduce friction.

The crank 50 is journalled in suitable bearings carried by the base for the housing and is the continuation of a shaft 52 upon which is mounted the gear 53 indicated in the drawings as being driven by another gear 54 which is in its turn driven by a motor indicated by the dotted line 55.

The housing 10 is separated from the crank case portion 10^b containing the gearing and crank 50 by means of a plate 60 provided at its central portion with an opening through which extends the lever 40. This opening designated by the numeral 61 is sealed against leakage of the refrigerant from the housing 10 to the opening 61, by means of a flexible sleeve or diaphragm 62, preferably in the form of an elastic metal bellows such as is commonly known in the trade under the name of sylphon, which sleeve is sealed, as by brazing, or otherwise secured to the plate 60 around the opening 61 and is at its upper end sealed by brazing or otherwise secured to a flat ring 63. This ring 63 is held tightly against disc or boss 45 on lever 40 by the upper end of forked member 43 which is in turn held tightly upon lever 40 by the nut 44. A suitable gasket 65 in groove 46 is provided in order to make a gas-tight closure of the upper end of the flexible sleeve 62, and likewise, a suitable gasket is provided between the plate 60 and the housing 10, as shown, to make a gas-tight connection between them.

The plate 60 and flexible sleeve or bellows 62 are so located longitudinally of the lever 40 that the axis of oscillation of the lever 40 (determined by the pivots 42) will pass through the normal longitudinal axis of the sleeve between the ends of the sleeve 62 and preferably at the point midway between the normal positions of the end planes of the sleeve. The word "normal" here refers to the positions of these elements of the bellows when the bellows is free and at rest. The purpose of this location is to permit the flexing of the sleeve in its natural manner and to reduce to a minimum the stresses set up during flexing, as explained below.

Fig. 5 illustrates the natural flexing of the bellows from which the location of the pivot axis 42 of the driving shaft is determined. In order to increase the life of the bellows under repeated flexing, and to decrease the resistance offered by the bellows to such flexing and thus decrease the amount of power re-

quired to drive the apparatus, it is desirable to eliminate side stresses on the bellows and to subject the bellows to the minimum stress for a given displacement or amount of flexing. 5 That is, when the bellows is flexed, all forces transmitted from one corrugation to the next should act in lines which are as nearly as possible perpendicular to the planes of the corrugations and should not have any component in a direction parallel to such planes. 10 And moreover such forces between any pair of corrugations should be a minimum for a given flexure of the bellows. If such a bellows is supported with one end fixed and with its axis in a vertical line and the other end of the bellows is free, the bellows will oscillate or vibrate freely when the free end has been subjected to a bending force applied at a single point and the force has been suddenly 15 removed. During this free vibration the bellows flexes in its natural manner and it will be evident that in such flexing the bending stresses set up in the bellows at any given point will be a minimum for a given amount 20 of flexure. In flexing naturally the bellows takes a form illustrated in Fig. 5 in which the normal axis *ab* always assumes the form of a simple curve *ab'* which I believe to be a circular arc normal to the end planes of the bellows. And I believe that the free end *cd* of the bellows always remains tangent to a sphere whose center is the point *e* located on the line *ab* midway between the normal positions of the end planes. 25 Accordingly I construct and arrange the bellows and the pivoted lever 40 so that during movement of the lever the bellows is constrained to flex in its natural manner, that is to say the plane of the free end of the bellows is maintained tangent to a sphere whose center is the point *e*. This is accomplished by locating the point of change of motion (that is, the pivot) of the member 40 at the point *e*. 30 Thus in Fig. 5 the lines *ae* and *eb'* represent the axes perpendicular to the end planes of the bellows and these lines always intersect at a point on the normal axis of the bellows midway between the normal positions of the end planes. The line *eb'* also represents the axis 35 of the portion of the lever 40 above the pivot 42. Thus during movement of the driving and driven members the bellows is flexed so as to oscillate between two positions on either side of its normal axis. In the case illustrated this oscillation is simple planar oscillation while in the embodiment of the invention shown in my application Serial No. 400,894 a portion of the bellows nutates, the point *e* being referred to as the center of oscillation 40 (or more specifically in cases where the bellows nutates, as the center of nutation). 45

As indicated in the drawings, particularly in Figs. 5 and 6, the preferred form of sleeve used for this purpose is a corrugated metallic 50 sleeve known in trade as a "sylphon". Such a

form of sleeve is well known and forms the subject of various patents already granted. This form of sleeve has been found to give satisfactory results, permitting the rapid actuation of the pump, forming an effective seal for the chamber or housing containing the pump, and offering only a very small resistance to the oscillation of lever 40 upon its pivots 42. 70

The pump and housing will of course be 75 provided with suitable inlets and outlets for fluid, such an inlet being indicated at 70, Fig. 2, and an outlet being indicated at 72, Fig. 1. The outlets, in the form shown, lead from small valve chambers 73 containing the stems 80 and springs of valves 71 which open outwardly from the ends of cylinders 11.

In Fig. 3 there is shown conventionally a system using the present form of compressor which latter is shown greatly enlarged to illustrate clearly its relation to the rest of the 85 system.

From this figure, it will be noted that in using the compressor herein described, a circuit is provided for the refrigerant, which 90 circuit presents no opportunity for leakage.

The refrigerant will pass from the compressor *P*, through conduit *P'*, into condenser *C*, then through conduit *C'* into the expansion chamber or coil indicated as enclosed 95 within a brine tank designated *E*. From the latter, the expanded refrigerant will be drawn by compressor *P* through conduit *E'*, again compressed and returned to the system. Suitable valves and control apparatus, not 100 forming a part of the present application will of course be provided.

The path of the gas through the compressor is, as may readily be seen, into the housing 10 through inlet 70, thence to the slotted portion 105 of the piston rod 13, then through passage 23, chamber 24, and valve 21, to the cylinder 11. Upon compression, the gas then passes through valve 71 into chamber 73 and through outlet 72 and thence to the condenser. 110 The portion of the housing 10 in direct communication with the inlet 70 may be termed the low-pressure chamber, while the conduit *P'* and chamber 73 in direct communication therewith may be termed the high-pressure 115 chamber.

It will be readily noted that by the use of a seal for the housing 10 enclosing the pump, a refrigeration system which is entirely sealed against leakage of refrigerant or oil from the system or air into the system, is provided. 120

While the description has indicated the driving of the pump by means of a crank and gearing connected to a motor, it will be readily understood that any suitable form of driving means may be used to actuate the pump, and such driving means will be designated in the claims by the expression "source of power" or "prime mover". 125

Further, while the specific description has 130

been confined to a pump for refrigeration apparatus, it will be readily understood that this form of pump may be found suitable for other forms of apparatus, and the invention should not be limited to this art.

Again, while the form of mechanism herein shown and described, constitutes preferred embodiment of one form of the invention, it will be understood that other forms might be adopted and various changes and alterations made in the shape, size, and proportion of the elements therein without departing from the spirit and scope of the invention.

What is claimed is as follows:

1. A compressor having a casing, a walking beam disposed within said casing, a bellows surrounding said beam near the center thereof, one end of the said bellows being hermetically sealed to the casing and the opposite end being similarly sealed to the said walking beam, a member extending outward from the said walking beam where said bellows is sealed thereto, arms extending laterally from said member toward the longitudinal center of said bellows and bearings for said arms at the approximate longitudinal center of said bellows.

2. A compressor having a casing, a walking beam disposed within said casing, a bellows surrounding said beam near the center thereof, one end of the said bellows being hermetically sealed to the casing and the opposite end being similarly sealed to the said walking beam, and a fulcrum for said beam at the approximate longitudinal center of the said bellows.

3. A refrigerant compressor comprising a pump chamber, a cylinder and piston associated therewith, a power train, a walking beam connecting the power train and piston, a gas-tight bellows connected at one end so as to cover the pump chamber and at the other end connected to the walking beam, and a trunnion support for said walking beam outside the bellows, the axis of said support being within the length of the bellows.

4. A refrigerant compressor comprising, a power train casing and a compressor casing, a walking beam extending from one casing into the other, a flexible gas-tight bellows with its ends connected to the walking beam and casing to form a gas-tight closure between the walking beam and compressor casing, a trunnion yoke carried by the walking beam with its axis within the length of the bellows and outside of the bellows, and support for said trunnion yoke.

5. A compressor casing, a cylinder having a piston therein mounted on the casing, a crank case extending laterally from said casing, a walking beam disposed within said casing and crank case, connecting means between one end of said beam and the piston, means for operating the opposite end of said beam, a bellows surrounding said beam near the

center thereof, one end of the said bellows being hermetically sealed to the surrounding crank case and the opposite end being similarly sealed to the said walking beam a member extending outward from the said walking beam, where said bellows is sealed thereto, arms extending laterally from said member toward the longitudinal center of said bellows, said arms being fulcrumed in said casing at the approximate longitudinal center of said bellows.

6. A compressor casing, a cylinder having a piston therein mounted on the casing, a crankcase extending laterally from said casing, a walking beam disposed within said casing and crank case, connecting means between one end of said beam and the said piston, means for operating the opposite end of said beam, a bellows surrounding said beam near the center thereof, one end of the said bellows being hermetically sealed to the surrounding crank case and the opposite end being similarly sealed to the said walking beam, a member extending outward from the said walking beam where said bellows is sealed thereto, arms extending laterally from said member toward the longitudinal center of said bellows, and bearings in said arms at the approximate longitudinal center of said bellows and bearing pins extending inward from said casing and engaging said bearings.

7. A compressor casing, a cylinder having a piston therein mounted on the casing, a crank case extending laterally from said casing, a walking beam disposed within said casing and crank case, connecting means between one end of said beam and the said piston, means for operating the opposite end of said beam, a bellows surrounding said beam near the center thereof, one end of the said bellows being hermetically sealed to the surrounding crank case and the opposite end being similarly sealed to the said walking beam, a member extending outward from the said walking beam where said bellows is sealed thereto, arms extending laterally from said member toward the longitudinal center of said bellows and bearings for said arms at the approximate longitudinal center of said bellows.

8. A compressor casing, a cylinder having a piston therein mounted on the casing, a crank case extending laterally from said casing, a walking beam disposed within said base and crank case, connecting means between one end of said beam and the said piston, means for operating the opposite end of said beam, a bellows surrounding said beam near the center thereof, one end of the said bellows being hermetically sealed to the surrounding casing and the opposite end being similarly sealed to said walking beam, and a fulcrum for said beam at the approximate longitudinal center of the said bellows.

9. A pump adapted for refrigerating sys-

tems comprising, a sealed air-tight housing, a compression chamber in the housing, displacement means for pumping gas from the compression chamber; and means for transmitting power through the wall of the housing for operating said displacement means, said power-transmitting means including a non-rotating, flexible tubular partition secured gas-tight over an opening through the wall of the housing and extending inwardly from the wall thereof; and a movable member extending through the partition for conveying movement to said displacement means.

10. A pump adapted for refrigerating systems comprising, a sealed air-tight housing, a compression chamber in the housing, displacement means for pumping gas from the compression chamber; and means for transmitting power through the wall of the housing for operating said displacement means, said power-transmitting means including a non-rotating, flexible tubular partition secured gas-tight over an opening through the wall of the housing, a movable member extending through the partition for conveying movement to said displacement means, and means for supporting the movable member from the housing comprising a U-shaped arm member rigidly secured to the movable member and having a bearing connection with said housing.

11. A pump adapted for refrigerating systems comprising, a sealed air-tight housing having a pump cylinder therein, a piston and connecting rod guided for reciprocating movement; and means for transmitting power through the wall of the housing for operating said piston, said power-transmitting means including a non-rotating, flexible tubular partition secured gas-tight over an opening through the wall of the housing, and a movable member extending through the partition in a direction approximately at right angles to the axis of said piston and having a slot connection with said piston rod.

12. A power transmitting device for pumps comprising in combination, a wall; and means for transmitting power through the wall including a movable power transmitting member and a partition sealed to the wall and connected to the member, the partition including a flexible tubular portion and the parts being so constructed and arranged that during movement of the member the central axes perpendicular to the end planes of the tubular portion intersect substantially midway between the normal positions of the ends of the tubular portion.

13. A power transmitting device for pumps comprising in combination, a wall; and means for transmitting power through the wall including a movable power transmitting member and a partition sealed to the wall and connected to the member, the partition including a flexible tubular portion and the parts

being so constructed and arranged that for a given flexure of the tubular portion the resistance to such flexure developed by the tubular portion is a minimum.

14. A power transmitting device for pumps comprising in combination, a wall; and means for transmitting power through the wall including a movable power transmitting member and a partition sealed to the wall and connected to the member, the partition including a flexible tubular portion and the parts being so constructed and arranged that during movement of the member the tubular portion partakes of its natural flexing movement.

15. A power transmitting device for pumps comprising in combination, a wall; and means for transmitting power through the wall including a movable power transmitting member and a partition sealed to the wall and connected to the member, the partition including a flexible tubular portion and the parts being so constructed and arranged that for a given displacement of the member the internal stress of any part of the tubular portion is a minimum.

16. A power transmitting device for pumps comprising in combination, a wall; and means for transmitting power through the wall including a movable power transmitting member and a partition sealed to the wall and connected to the member, the partition including a flexible tubular portion made of metal and the parts being so constructed and arranged that during movement of the member the central axes perpendicular to the end planes of the tubular portion intersect between the normal positions of the end planes of the tubular portion.

17. A power transmitting device for pumps comprising in combination, a wall; and means for transmitting power through the wall including a movable power transmitting member and a partition sealed to the wall and connected to the member, the partition including a flexible corrugated metal bellows connected to the member, the parts being so constructed and arranged that for a given flexure of the bellows the deformation of any corrugation is a minimum.

18. A power transmitting device for pumps comprising in combination, a wall; and means for transmitting power through the wall including a movable power transmitting member, and a partition sealed to the wall and connected to the member, the partition including a flexible tubular portion, and the member having an oscillating portion so disposed that the center of oscillation is substantially midway between the normal positions of the end planes of the tubular portion.

19. A power transmitting device for pumps comprising in combination, a wall; and means for transmitting power through the wall including a movable power transmitting member and a partition sealed to the wall and

- connected to the member, the partition including a flexible tubular portion and the parts being so constructed and arranged that during movement of the member a part of the flexible tubular portion oscillates about a center substantially midway between the normal positions of the end planes of the tubular portion.
- 5 20. A power transmitting device for pumps comprising in combination, a wall; and means for transmitting power through the wall including a movable power transmitting member and a partition sealed to the wall and connected to the member, the partition including a flexible tubular portion and the parts being so constructed and arranged that during the movement of the member the plane of one end of the tubular portion remains tangent to a sphere whose center is substantially at the center of the normal axis of the tubular portion.
- 10 21. In an apparatus of the character described, the combination of a pump having a housing; a driving means; and a sealed driving connection between the driving means and the pump comprising a flexible tubular partition sealed to the housing and a movable member extending from the driving means through the partition for conveying the movement of the driving means to the pump, said movable member being so mounted as to provide a natural flexing of the partition.
- 15 22. In an apparatus of the class described, the combination of a pump having a housing; driving means; and a sealed driving connection between the driving means and the pump comprising a bellows sealed to the housing and a movable member extending from the driving means through the bellows for conveying the movement of the driving means to the pump, said movable member being mounted to rock about a fixed axis intermediate the ends of the bellows.
- 20 23. In an apparatus of the character described, the combination of a pump; driving means; and a sealed driving connection between the driving means and the pump comprising a bellows sealed to the housing, a movable member extending from the driving means through the bellows for conveying the movement of the driving means to the pump, and bearing means for the movable member outside of the bellows so constructed and arranged as to permit natural flexing of the bellows.
- 25 55. In testimony whereof I hereto affix my signature.

JESSE G. KING.
